FIG. 1 is a perspective view of a rod holder showing the claimed design;

FIG. 2 is top view of that seen in FIG. 1;

FIG. 3 is a bottom view of that seen in FIG. 1;

FIG. 4 is a front view of that seen in FIG. 1;

FIG. 5 is a back view of that seen in FIG. 1;

FIG. 6 is a left side view of that seen in FIG. 1;

FIG. 7 is right side view of that seen in FIG. 1; and,

FIG. 8 is an alternate right side view of that seen in FIG. 1, here showing the back plate separated from the front plate. The dash, space, dash type broken lines are included for illustrating environmental structure and form no part of the claimed design.

1 Claim, 7 Drawing Sheets
